UNITED STATES PATENT OFFICE.

JOHN W. SUTTON, OF BROOKLYN, NEW YORK.

MACHINE FOR PLUCKING PELTS.

SPECIFICATION forming part of Letters Patent No. 536,742, dated April 2, 1895.

Application filed April 11, 1894. Serial No. 507,102. (No model.) Patented in England June 7, 1894, No. 11,102.

To all whom it may concern:

Be it known that I, JOHN W. SUTTON, a citizen of the United States, residing in Brooklyn, in the county of Kings and State of New York, have invented certain new and useful Improvements in Machines for Plucking Pelts, (patented in England June 7, 1894, No. 11,102,) of which the following is a specification.

10 This invention relates to certain improvements in the machine for plucking furs, for which Letters Patent were granted to me heretofore, No. 383,258, dated May 28, 1888, said improvements being designed with the 15 view of overcoming some of the defects of the machine referred to, facilitating the working of the machine, adjusting the pelt quickly to the required position toward the operative parts of the machine and permitting the 20 interruption of the cutting-off of the water-hairs whenever this is desired during the working of the machine.

The invention consists of a machine for removing the water-hairs from pelts of all kinds, 25 which comprises a fixed stretcher-bar, means for stretching and intermittently feeding a pelt over said stretcher-bar, a rotary brush located above the stretcher-bar and near the edge of the same, a reciprocating guard-comb 30 below the stretcher-bar, a rotary separating-brush likewise below the stretcher-bar, mechanism for moving the said brush and guard-comb into a position in upward and forward direction toward the edge of the stretcher- 35 bar and over the portion of the pelt below the same, a vertically-reciprocating knife, a rotary knife arranged to cut off the projecting water-hairs in conjunction with the vertically-reciprocating knife, and a card arranged 40 on the arm of the rotary knife at some distance from the same, so as to pass over the portion of the pelt in position on the stretcher-bar.

The invention consists, further, of mechanism for adjusting the apron to which the 45 pelt is applied, so as to adjust the pelt quickly on the stretcher-bar and bring any portion of the pelt into proper position relatively to the working parts of the machine.

The invention consists, further, of certain 50 operating mechanism connecting the driving-shaft with the reciprocating guard-comb and

separating-brush, whereby the same are operated at the proper time.

The invention consists, further, of means for withdrawing the vertically reciprocating 55 knife so as to lower it and prevent its action.

The invention consists, lastly, of certain mechanisms by which the motion is transmitted to the working parts of the machine, which mechanisms will be fully described hereinafter and finally pointed out in the claims.

In the accompanying drawings, Figure 1 is a plan view of my improved machine for plucking pelts. Fig. 2 is a side-elevation of the same. Fig. 3 is a detail side-view, partly 65 in section, of the mechanism for withdrawing the operating pawl and check-pawl from the ratchet-wheel by which the pelt is adjusted on the stretcher-bar. Fig. 4 is a vertical longitudinal section on line 4, 4, Fig. 1. Fig. 5 is likewise a vertical longitudinal section 70 of a portion of Fig. 1, on line 5, 5, Fig. 1, showing the mechanism for lowering the vertically-reciprocating knife, so as to throw the same out of action. Fig. 6 is a detail vertical 75 transverse section on line 6, 6, Fig. 1. Figs. 7, 8 and 9 are detail vertical sections showing the operating parts of the machine in their relative position toward the pelt on the stretcher-bar, said figures showing respect- 80 ively the position of the parts before the cutting off of the water-hairs takes place, during the act of cutting them off, and after the same are cut off. Fig. 10 is a detail front-view of a portion of the guard-comb, arranged below the 85 stretcher-bar, and Figs. 11 and 12 are respect- 90 ively a vertical longitudinal section and a plan of the adjustable bearing for the rotary brush above the stretcher-bar.

Similar letters of reference indicate corresponding parts.

In the drawings A is the frame of the machine and A' is the main driving-shaft which is journaled in suitable bearings of the frame A and provided with a fixed and a loose belt-pulley A² and A³ upon either of which the driving-belt A⁴ can be shifted by means of the belt-shifting lever A⁵ that extends to the front or working end of the machine. A belt A⁶ passes over a pulley A⁷ on the shaft A' and 95 over a pulley A⁸ on a short shaft A⁹ located at the working end of the machine, which 100

shaft A⁹ has a crank-handle A¹⁰ for turning it, in case the machine is to be worked by hand for adjusting the different parts before power is applied to the machine. A pinion B⁵ on the main-shaft A' engages a cog-wheel B'⁶ and transmits rotary motion to the cam-shaft C, which by means of the bevel cog-wheels B² B³ transmits rotary motion to a shaft B³ which is mounted at one side of the main-frame, the shaft B³ transmitting by the bevel cog-wheels B⁴ B⁵ rotary motion to a shaft B⁵, mounted transversely at the working end of the machine. The shaft B⁵ has radial arms B⁶ to the ends of which the rotary blade D is bolted or screwed. A brush D' of the same length as the blade D is supported by means of angle-pieces D² on the arms B⁶ in such a manner that it is located a short distance from the cutting edges of the blade D and so that the ends of its bristles extend slightly beyond the circle described by the cutting edge of the blade during the rotary movement of the same.

A knife-edged stretcher-bar E is fastened transversely on the machine-frame A, the edge of the stretcher-bar being a short distance from the circle described by the edge of the blade D, as shown in Figs. 7, 8 and 9. A rotary cylindrical brush F is arranged directly above the stretcher-bar E and at a short distance back of the edge of the same. The ends of the shaft F' of said brush are mounted in stationary bearings on plates F², which are hinged to plates F³ that are fastened by screws F⁴ which pass through longitudinal slots F⁵ in the plates F³ into supports of the main-frame A, so as to permit the proper adjustment of the brush toward the edge of the stretcher-bar E. The hinged plates F² have apertures F⁶ through which a wrench or other implement can be passed to tighten or loosen the screws F⁴, as shown in Figs. 11 and 12. Thumb-screws F⁷ pass through the notches in the free ends of the plates F² and screw into threaded bushings of the plates F³, while helical springs F⁸ are interposed between the plates F² F³ and press the plates F² in upward direction. By turning the thumb-screws F⁷ in one direction or the other, the 50 bearings for the rotary brush F can be readily raised or lowered so as to adjust the brush according to the kind or condition of the pelt under treatment. The brush F is rotated by means of cords or belts F⁹ and suitable pulleys from the main-shaft A'.

The cam-shaft C carries at each end a cam C' which acts on anti-friction rollers C² projecting from the sides of horizontally-reciprocating bars G, which are guided by slots C³ on the cam-shaft C. The bars G are connected by intermediate threaded rods G² and nuts and jaw-nuts g g, with cross-heads G', said cross-heads being guided in brackets g² of the frame A. The rods G² and nuts g g serve for adjusting the distance of the cross-heads G' from the shaft C. To the cross-heads G' are pivoted the rear-ends of two le-

ver-arms H and J, which are again connected by pivot-links H' and J' with fixed supports on the main-frame A, as shown in Figs. 4 and 7, by which the motion of the lever-arms H and J is properly governed. The free ends of the arms H are curved upward and provided with bearings in which the shaft of a cylindrical separating brush K is mounted, which brush is rotated from the main-shaft A' by means of endless cords or belts K' which pass over pulleys on the main-shaft and on the brush-shaft, said belts passing around idlers K³ which are connected by tension-springs K² with the floor or other fixed point so that said belts are at all times kept taut, as shown in Fig. 2.

To the ends of the arms J is attached an upwardly-projecting metallic comb L, which is shown in detail in Fig. 10. A vertically-reciprocating knife M extends across the main-frame and is supported by a transverse knife-holder M' which is guided in slotted ways M² in the sides of the main-frame A.

Elastic buffers M³ of any suitable construction are provided on the main-frame at the lower-end of the ways M², so as to cushion the knife-holder M' when the knife is lowered and moved away from the stretcher-bar. The edge of the knife M is vertically below the edge of the stretcher-bar E, as shown in Fig. 7. The knife-holder M' is supported on adjustable blocks N' mounted on the front-ends of pivoted cam-levers N, one on each side of the main frame, which levers are provided at their rear ends with tappets N² that are actuated by cams N³ on the cam-shaft C. Each cam-lever N is fulcrumed to slide-plates O which are guided by slots n on headed screws n' at the inner sides of the frame A, as shown in Figs. 4 and 6. The lower ends of the slide-plates O are pivotally connected with the upper end of a toggle-lever O', the lower end of which is pivoted to the main-frame A, as shown in Figs. 4 and 5, while the knuckle-joint is connected by a link O² with a fixed arm O³ on a rock-shaft O⁴, that is mounted on the main-frame and provided at each end with a handle-lever O⁵ for turning it. When the handle-lever O⁵, the slide-plates O and the parts connecting the same are in the position shown in Fig. 5, the tappets N² of the levers N are out of the path of the cams N³ and the knife M is not reciprocated, but remains stationary in its lowermost position. When the slide-plates O are raised by placing the handle-lever O⁵ in the position shown in Fig. 2, the tappets at the rear-ends of the levers N are placed into the path of the cams N³ and the knife M is raised at the proper time and permitted to drop when the cams have passed over the tappets N² so that the front-ends of the levers N descend until the knife-holder M' is arrested by the buffers N³.

The apron P on which the pelt a to be treated is spread and fastened, is attached at its ends to two drums Q and R which are mounted transversely on the main-frame and

supported in suitable bearings of the same. The apron P passes from the roller Q over a tension-roller S supported by means of helical springs S' on stationary arms S² of the main-frame A, then over and around the stretcher-bar E to the roller R. Cog-wheels Q' and R' are mounted on the shafts of the drums Q and R and are engaged by a pinion R² on a shaft carrying a ratchet-wheel R³ that is engaged by check-pawl T pivoted to the main-frame A, while an actuating pawl T' is pivoted to a lever T², which is fulcrumed at T³ to the frame, and provided at its upper end with a curved part T⁴ which is acted on by a roller T⁵ on the cog-wheel B'. A spring t connects the lower end of the fulcrumed lever T² with the main-frame and presses the lever T² against a fixed buffer-bracket t'. The shaft of the ratchet-wheel R³ also carries a pendent frame U which is provided with two arms having at their ends flanges U' extending over the rim of the ratchet-wheel R³, which flanges are provided with notches for receiving the ends of the pawls T T' as shown in Figs. 2 and 3. When the frame U is swung into the position shown in Fig. 3, the flanges U' engage the ends of the pawls and prevent them from acting on the teeth of the ratchet-wheel R³. At each rotation of the cog-wheel B' the roller T⁵ engages the upper end of the lever T², oscillates the same and moves the pawl T' into one or more teeth of the ratchet-wheel R³, so that when the roller T⁵ has passed the end of the lever T², the spring t returns it to its former position and turns the ratchet-wheel T³ by the pawl T' which motion is transmitted by the pinion R² to the cog-wheels Q' and R' and drums Q and R, so that the apron P is intermittently fed over the stretcher-bar E, being unwound from the drum Q and wound up on the drum R.

When the frame U hangs vertically, as shown in Fig. 2, the pawls T and T' are not engaged by the notched flanges V' and are free to engage the teeth of the ratchet-wheel R³. When the frame U is moved into the position shown in Fig. 3, a pinion V which is in mesh with the cog-wheel Q' can be turned by its crank-handle V' and thereby the apron and the pelt thereon be shifted in either direction into any required position, as may be necessary for working the apron on one drum and unwinding it from the other.

The operation is as follows: The pelt a having been stretched and secured on the apron P and having been so adjusted that one end of the same is near the stretcher-bar E, the machine is started. At each rotation of the cam-shaft C, the pawl T' is actuated and the ratchet-wheel R³ turned for the distance of one tooth, whereby the roller Q is turned so as to unwind a short length of the apron while the roller R is turned in the opposite direction, so as to wind up a corresponding length of the apron. In this manner the apron and with it the pelt is fed intermittently over the edge of the stretcher-bar E so that narrow strips of the

pelt are subjected successively to the action of the operating devices. During the forward motion of the pelt, the rotary brush F which is located above the stretcher-bar, exerts a very peculiar action upon the fur and the stiff hairs of the pelt. It stirs up the fur and hairs and causes the hairs to rise and free themselves from the surrounding fur or soft hairs, which latter are straightened by the continuous action of the quickly-rotating brush and laid down flat on the pelt. The rotary brush K below the stretcher-bar is next moved by the lever-arms H and cross-heads G' in forward and upward direction as shown in Fig. 7, so as to brush back the fur and separate it from the stiff hairs which project from the pelt in the direction of the stretcher-bar. These separating-brush K is then moved in backward and downward direction, so as to be out of the path of the guard-comb, which is moved from its lowermost position in upward and backward direction until it arrives at the under side of the pelt close to the edge of the stretcher-bar, as shown in Fig. 8, in which position it retains the soft fur, and protects it against the action of the cutting knives. The knife M is next raised until its cutting edge is in close proximity to the edge of that portion of the pelt which is at the time in front of the edge of the stretcher-bar. When the rotary blade D arrives with the cutting edge in front of the stretcher-bar, as shown in Fig. 8, the cutting edges take hold of the stiff hairs and shear them close to the skin of the pelt, without cutting off any portion of the soft hair. The apron is next actuated and the next adjacent strip of pelt fed forward and placed over the edge of the stretcher-bar. The vertical cutting knife recedes then from the stretcher-bar while the rotary knife moves on until the brush D' arrives in front of the pelt and sweeps across that part in front of the edge of the stretcher-bar. The brush D' draws out the fur and hairs from under the upper rotary brush and places them in proper condition for the action of the lower separating-brush which is then moved up toward the lower edge of the pelt so as to brush back the fur below the edge and separate it from the stiff hairs, while the upper brush keeps down the fur above the edge of the stretcher-bar. The separating brush is then moved back again and the guard-comb moved up so as to protect the fur while the next cutting action of the knives takes place and so on.

As compared to my prior patent before mentioned, the novel and important feature of the present construction is the substitution for the stationary card above the stretcher-bar, of a rotary brush which is placed close to the edge of the stretcher-bar and which serves to brush the fur back from the edge of the bar while it allows the stiff hairs to rise and project above the fur. When the card which was supported back of the rotary knife in my prior machine, passed the edge

of the stretcher-bar, it drew out from under the stationary card all the fur and hair on that section of the pelt that were on the edge of the bar. Some of the fur however was only 5 partly drawn out, owing to the varying thicknesses of the pelts. This partly drawn out fur lay in the form of a loop which stood out far enough to be reached by the knives but not far enough to be drawn down by the rotary brush below the stretcher-bar, and so was 10 cut off by the knives. With the rotary brush in place of the stationary card heretofore used by me, this looped fur is drawn back and laid down before the knives reach it so that 15 the cutting of the fur is prevented and only the stiff hairs are removed.

When a pelt is put on the apron, and the machine is started it requires a few rotations of the shafts until a perfect separation of the 20 fur from the stiff hairs on the front section of the pelt acted upon takes place. If the knives were to act on this portion of the pelt it would be injured as some of the fur would be cut off with the hairs. Formerly guard-plates of thin 25 metal were used to prevent the cutting of this fur, but they covered up the pelt so that the progress of the work could not be seen. For dispensing with the covering plates, the mechanism of interrupting the motion of the reciprocating 30 knife is introduced, which has the advantage that the knife is prevented from rising until the separation of the fur and hairs is accomplished by the other operative parts 35 of the machine. As soon as this separation is obtained, the reciprocating knife is thrown instantly into action by moving the handle-lever O⁶ forward, and setting its actuating mechanism in motion. This has also the further advantage that the action of the cutting knives 40 can be instantly interrupted whenever this should be required, in case one or the other of the brushes or the rotating card or the guard-comb should fail to properly perform its work, or when for some reason or another a portion 45 of the pelt should not be subjected to the action of the cutting knives. The entire machine is thereby more completely under the control of the attendant and performs its work in a quicker, better and more reliable manner 50 than the machine heretofore patented by me.

Having thus described my invention, I claim as new and desire to secure by Letters Patent—

1. The combination of a stretcher-bar, 55 means for intermittently feeding a pelt over the stretcher-bar in one direction, a rotary brush located near the edge of the stretcher-bar and in contact with that portion of the pelt moving toward the edge of the stretcher-bar, means for continuously rotating said brush reversely to the direction of the movement of the pelt, and means for removing the hairs projecting from the pelt in front of the working edge of the stretcher-bar, after 60 the brush has operated on the pelt, substantially as set forth.

2. The combination of a stretcher-bar,

means for intermittently feeding a pelt over the stretcher-bar in one direction, a rotary brush located near the edge of the stretcher-bar and in contact with that portion of the pelt moving toward the edge of the stretcher-bar, means for continuously rotating said brush reversely to the direction of motion of the pelt, a vertically reciprocating knife, a rotary knife, said knives co-operating to remove the hairs projecting from the pelt in front of the working edge of the stretcher-bar, after the rotary brush has operated on the pelt, and a brush applied to the supporting-arms of the 80 rotary knife back of the same, substantially as set forth.

3. The combination of a stretcher-bar, means for intermittently feeding a pelt over the stretcher-bar in one direction, a rotary brush located near the edge of the stretcher-bar and in contact with that portion of the pelt moving toward the edge of the stretcher-bar, means for continuously rotating said brush reversely to the direction of movement 90 of the pelt, a rotary separating-brush below the stretcher-bar and a mechanism by which the separating-brush is moved upward and forward into a position close to the working edge of the stretcher-bar, substantially as set 95 forth.

4. The combination of a fixed stretcher-bar, means for intermittently feeding the pelt over the working edge of the stretcher-bar, a rotary brush above and in close proximity to the 100 stretcher-bar, said brush being arranged back of the working edge of the stretcher-bar, means for rotating said brush reversely to the direction of motion of the feeding means, a rotary separating brush below the stretcher 105 bar, a reciprocating guard comb also below the stretcher bar, mechanism whereby the separating brush is moved upward and forward to the working edge of the stretcher bar and back again, and mechanism by which the 110 guard comb is moved upward and under the stretcher bar near the working edge of the same, substantially as set forth.

5. The combination of a stretcher-bar, means for intermittently feeding a pelt over 115 the working edge of the same, a rotary brush located near the edge of the stretcher-bar and in contact with that portion of the pelt moving toward the edge of the stretcher-bar, a cam-shaft, cams on said shaft, reciprocating 120 cross-heads guided on the main-frame and operated by said cams, lever-arms pivoted to said cross-heads below the stretcher-bar, a rotary brush mounted on the ends of one set of arms, a comb mounted on the ends of the 125 other set of arms, and pivot-links, connecting the arms with the frame, whereby said brush and comb are moved toward and away from the edge of the stretcher-bar, substantially as set forth.

6. The combination, of a stretcher-bar, means for intermittently feeding a pelt over the edge of said bar, a rotary brush mounted above the stretcher-bar and near the edge of

the same, hinged plates on which the shaft of said brush is mounted, springs for pushing said hinged plates upward, screws for pressing them downward, and means for adjusting the 5 said plates and brush in horizontal direction, substantially as set forth.

7. The combination, of a stretcher - bar, means for intermittently feeding a pelt over the same, a rotary brush above the stretcher-bar, a rotary separating-brush below the same, a guard-comb also below the stretcher-bar, a rotary cutting-blade, a vertically-reciprocating-knife, and mechanism for throwing the reciprocating-knife in or out of action, substantially as set forth.

8. The combination, of a stretcher - bar, means for intermittently feeding a pelt over the same, a rotary brush above the stretcher-bar, a rotary brush below the same, a guard-comb, a rotary cutting knife, a vertically cutting knife, a cam-shaft, cams on the same, intermediate lever-arms for reciprocating said knife, slide-plates to which the lever-arms are fulcrumed, and means for raising or lowering 25 said slide-plates so as to throw the lever-

arms of the vertical knife in or out of action, substantially as set forth.

9. The combination, of a stretcher-bar, an apron stretched over the same, to which the pelt is attached, drums to which the apron is 30 attached, a pawl and ratchet-mechanism connected with said drums, a cam-shaft, means for actuating said pawl and ratchet-mechanism from said cam-shaft, a pendent frame pivoted to the shaft of the ratchet-wheel and provided with guard-flanges for engaging the actuating pawl and check-pawl of the ratchet-wheel and throwing said pawls out of engagement with said ratchet-wheel, and means for rotating the drums when said pawls are out of 40 engagement so as to permit the quick adjustment of the apron on the drums in either direction, substantially as set forth.

In testimony that I claim the foregoing as my invention I have signed my name in presence of two subscribing witnesses.

JOHN W. SUTTON.
